INVENTOR
ALBERT L. WIDDIS.
BY

H. C. Dickman
ATTORNEY.

UNITED STATES PATENT OFFICE

ALBERT L. WIDDIS, OF HARRISVILLE, MICHIGAN

ANTIFRICTION ATTACHMENT FOR VESSELS

Application filed October 23, 1929. Serial No. 401,665.

This invention relates to an attachment for vessels, the prime object of which is to reduce the friction of the water against the vessel, to increase the buoyancy of the vessel, to aid in propulsion both by rearward force 5 and also by reducing the vacuum pull at the stern.

Still another object is to provide an attachment for vessels whereby barnacles or other marine growth are prevented from gathering 10 on the sides of the vessel, and removing them therefrom.

A further object is to provide baffles on the hull whereby the stream of air is momentarily trapped, thus aiding the buoyancy of 15 the vessel, and also reducing the water friction.

Other objects, advantages and features of 20 invention may appear from the accompanying drawing, the subjoined detailed description, and the appended claims.

In the drawing

Figure 1 is a fragmentary, longitudinal, sectional view of a vessel embodying my invention. 25

Figure 2 is a transverse sectional view of a vessel embodying my invention.

Figure 3 is a fragmentary rear elevation of a square stern vessel.

Figure 4 is an enlarged, longitudinal, sectional view of a sectional pipe which might 30 be utilized in my invention.

Referring more particularly to the drawing, the numeral 1 indicates the hull of a vessel which may be of any desired shape, size 35 or character. A pipe 2 extends longitudinally of the vessel, either along the keel or along the sides, or either or both, and this pipe starts at approximately the water line 40 at the bow and extends to approximately the water line in the stern.

As shown in Figures 1 and 2, the pipe 2 extends along the keel and this pipe is perforated throughout its entire length so that air 45 may escape from the pipe throughout its entire length. A plurality of air inlet pipes 3 extend into the pipe 2, and a valve or valves 4 is provided in the pipe so that sections thereof can be closed off. That is, when the 50 vessel is not loaded, it will ride higher in

the water, and therefore upper sections of the pipe must be closed off.

Extending substantially from bow to stern, and preferably horizontally, are a plurality of baffles 5. These baffles trap the air as it rises from the pipe 2 and hold it for a period of time against the hull, thus materially aiding in the reduction of friction because the friction of the water against the air will not be as great as that of water against metal or wood. Also the baffles 5 are aids in buoying 55 the vessel. Certain noxious gases can be blown through the pipe 2 and these gases when they rise around the vessel will remove 60 barnacles or other marine growth, and prevent them from lodging on the hull. 65

In Figure 3, a square sternen vessel is shown, and in order that the vacuum at the stern may be more effectively broken, I provide transverse pipes 6—7 at the stern, which 70 extend from the main longitudinal pipe 8. All of these pipes are perforated as previously described, to permit the escape of air therefrom. The holes in the pipe are all directed 75 outwardly and rearwardly so that the force of the air or gas will tend to propel the vessel.

In Figure 4, I have illustrated a sectional pipe which extends lengthwise of the vessel. The pipe 9 is made up of a plurality of sections 80 10 which will screw together and the outer walls taper rearwardly so that the holes 11 through the walls extend outwardly and rearwardly for the purpose of propelling the vessel. The holes may also extend through 85 the pipe so that no appreciable propelling force is provided.

Having described my invention, I claim:

1. An attachment for vessels comprising a pipe extending from substantially the water line at the bow to the water line at the stern, means to secure said pipe to the vessel, said pipe having holes therein which extend outwardly and rearwardly, and intake pipes extending into said first named pipe, and baffles on the hull of the vessel, said baffles extending substantially the length of the vessel. 90
2. An attachment for vessels comprising a pipe extending from substantially the water 95

2. An attachment for vessels comprising a pipe extending from substantially the water 100

line at the bow to the water line at the stern, means to secure said pipe to the vessel, said pipe having holes therein which extend outwardly and rearwardly, and intake pipes extending into said first named pipes, and transverse perforated pipes at the stern of the vessel.

3. An attachment for vessels comprising a pipe extending from substantially the water line at the bow to the water line at the stern, means to secure said pipe to the vessel, said pipe having holes therein which extend outwardly and rearwardly, and intake pipes extending into said first named pipes, valve means in the pipe, said pipe including a plurality of sections tapering rearwardly and the perforations extending through the tapered walls of said sections.

4. An attachment for vessels comprising a pipe extending along the keel from substantially the water line at the bow to the water line at the stern, said pipe having perforations throughout the length thereof, intake pipes in said first named pipe and transverse pipes at the stern communicating with said first named pipe.

In testimony whereof, I affix my signature.
ALBERT L. WIDDIS.
